(57) **CLAIM**

We claim the ornamental design for an appliance knob, as shown and described.

DESCRIPTION

FIG. 1 is a front perspective view of an appliance knob showing our new design;

FIG. 2 is a front elevation view of the appliance knob of FIG. 1;

FIG. 3 is a rear elevation view of the appliance knob of FIG. 1;

FIG. 4 is a top plan view of the appliance knob of FIG. 1;

FIG. 5 is a bottom plan view of the appliance knob of FIG. 1; and,

FIG. 6 is a first side elevation view of the appliance knob of FIG. 1, with the second side elevation view being a mirror image of the first side elevation view.

The features shown in broken lines depict environmental subject matter only and form no part of the claimed design.
